ABRASIVE SALVAGING APPARATUS

Lemuel M. Gilbert, Oaklyn, N. J., and
Carl G. Derr, Philadelphia, Pa.

Application December 1, 1947, Serial No. 789,084

19 Claims. (Cl. 209—13)

This invention relates in general to a process and an apparatus for the salvaging of abrasive material after use and its recirculation or return to mechanism operating on stone. The principal object of the invention is the provision of an efficient apparatus and an associated process for the recovery of abrasive material subsequent to its employment in the cutting, grinding, and/or polishing of stone, such as utilized in building construction, monuments and the like. Another object is to provide an abrasive salvaging apparatus, particularly designed and adapted for the stone cutting and polishing industry and effective to recover a large percentage of the abrasive material hitherto lost or discarded after use.

Another object is the provision of an apparatus for the recovery and reclaiming of abrasive material from the residue deposited by the grinding, cutting, and/or polishing of stone material with water as an abrasive carrier.

A further object is to provide an apparatus of the kind indicated and adapted for association with stone cutting, grinding, polishing, and/or similar purpose machines, and effective to reclaim abrasive material and return same, after use, to the machine operating on the stone in order to assure a working supply of the abrasive material while the operation is in progress.

With the foregoing and other objects in view, which will appear as the invention proceeds, the invention resides in the combination and arrangement of parts, and in the details of construction hereinafter described and claimed, it being understood that various changes in the preferred embodiment of the invention herein disclosed may be made within the scope of what is claimed without departing from the spirit of the invention.

The preferred embodiment of the invention is illustrated in the accompanying drawings, wherein:

Figure 1 is a side elevational view of an apparatus embodying the invention, certain parts being broken away for clarity of illustration, and showing various component parts in operative relation for the salvaging of abrasive material;

Fig. 2 is a plan view of the apparatus shown in Figure 1, with certain portions broken out to more clearly depict the interior arrangement of parts;

Fig. 3 is an enlarged, fragmentary, sectional, elevational view of the pulsator mechanism which functions to initially receive the wet residue mix-

ture of abrasive and stone dust and intermittently eject it by an air blast to a circulating unit.

Fig. 4 is an enlarged, fragmentary, elevational, sectional view of the means for automatically connecting and disconnecting certain component parts associated with the pulsator mechanism; the view being taken on line 4—4 of Fig. 2, and as seen in the direction of the arrows:

Fig. 5 is a longitudinal, sectional view, partly in elevation and with parts broken away, of the abrasive circulating and collecting unit and parts associated therewith;

Fig. 6 is an enlarged, transverse, sectional view, taken on the line 6—6 of Fig. 1, and as seen in the direction of the arrows;

Fig. 7 is a longitudinal, sectional view of an abrasive circulating unit and parts associated therewith;

Fig. 8 is a side elevational view of a perforated washing pipe, which functions to remove abrasive material from the inner periphery of the drum;

Fig. 9 is a fragmentary, perspective view of one of the abrasive scoops or conveyor buckets, which line the interior of the abrasive collecting drum;

Fig. 10 is an enlarged, fragmentary, perspective view of one of the abrasive receiving trays or hoppers arranged on the inner periphery of the collecting drum;

Fig. 11 is a view similar to Fig. 10 and showing the adjustable means for varying the amount of abrasive it is desired to receive in the hopper; and

Fig. 12 is a fragmentary, perspective view of mechanism for leveling and tilting the abrasive washing and collecting drum.

In cutting stone material into blocks or into desired configurations, such as for example, are customarily found in monument works, the stone is cut by saws or endless wire cables, and when the latter type of cutting means is employed, abrasive material carried by water is continuously applied to the travelling cable. The residue from this stone cutting operation, consisting substantially of stone dust and abrasive particles, is customarily discarded, but in accordance with the present invention, the abrasive material in this residue may now be salvaged and re-employed. Stone grinding and polishing operations also require considerable quantities of abrasive, and hitherto there appears to have been no apparatus effective for the reclaiming of the abrasive on a commercial scale.

Broadly, the present abrasive salvaging process contemplates the flotation and carrying off of the lighter stone dust particles and the scoop-

ing up, washing and collection of the heavier abrasive particles in a series of steps which achieves the reclamation of a high percentage of the original abrasive material in form suitable for immediate use. The various steps in the reclamation process include the initial conveyance of the abrasive residue material in suspension with water and via suitable guide means, into a pulsator unit which intermittently receives air under comparatively high pressure that is effective to force the moist abrasive residue upwardly to a circulating unit, from whence it descends by gravity to the inner bottom of a water-containing and slowly rotating collector drum. Buckets or scoops on the inner periphery of this drum convey the comparatively heavy abrasive particles from the bottom of the drum for deposit into a chute, whence they are returned to the stone cutting or polishing means (not shown), through the intermediary of an adjustable water medium, for reuse. Simultaneously with this processing and reclamation of the abrasive material, the residue material in suspension in the water in the drum and consisting principally of stone dust and a slight percentage of finely divided abrasive particles of flour-like consistency, is floated out from the drum and falls on a series of splash trays arranged in a tank and to which the heavier abrasive particles cling while the lighter and unusable particles together with the stone dust are carried off and discarded.

Referring now in detail to the drawings, wherein similar characters of reference indicate corresponding parts in the various views of the preferred form of the invention, the numeral 21 designates generally a supporting frame, wherein a tank 22 is suitably secured. Across this tank and fastened to opposite edges thereof at the upper edges is a pair of channel bars 23, 24, arranged in spaced relation and having secured to their outer ends a pair of triangular-shaped brackets 25, 26 respectively. On a pivot pin or axle rod 27, secured to and joining the spaced brackets 25, 26, a frame or cradle 28 is rockably and adjustably supported in normal horizontal position, as best shown in Figs. 1 and 5. To maintain the cradle 28 in the position shown or to tilt same when desired, a manually operable adjusting rod 29 is threadedly engaged in a block 30 pivoted on a stud or bolt 31 secured in a bracket or lug 32 fastened to an adjacent portion of the cradle 28. The lower end of the rod 29 terminates in a ball (not shown), which is angularly and rotatably received in a socket block 33 fastened to an angle bar 34 in turn secured to the channel bars 23, 24. It will be understood by inspection of Fig. 5 that when the adjusting rod 29 is turned by the hand-wheel 29a fastened thereto, the cradle frame 28 may be aligned horizontally to maintain an even level of its liquid contents, or tilted to facilitate the cleaning or dumping of the material therein.

The frame 28, as best shown in Figs. 1 and 2, also serves as a support for a number of the other units of the apparatus and including the driving motor 35, the circulating cylinder 36, the washing and collecting drum 37, and various operating parts and details associated therewith, as hereinafter described. By further inspection of Figs. 1 and 2, it will be seen that the driving motor 35 which is mounted on a bed plate 38 forming a part of the frame 28, has its shaft 39 operably connected to a gear reduction unit 40, the shaft of which is provided with a pinion

41 meshing with a comparatively large gear 42 secured to a centrally positioned shaft 43 rotatably secured in bearing brackets 44, 45 fastened to the bed plate 38. To the left-hand side of the collecting drum 37, whose lower periphery partially protrudes through the cradle 28, a closure plate 46 is detachably secured by screws 47 welded at one end, as at 47a, to the adjacent surface of the drum, and clamped by nuts 48 against lugs 49 formed on the closure plate 46 which normally seals the left-hand end of the said drum. When desired, the plate 46 may be removed for inspection of the interior of the drum or for any adjustments of parts therein. The central shaft 43 is fastened to a coupling member or plate 50 fastened by screws 51 to the closure plate 46 so that when the shaft 43 is turned, the plate 46 and the attached drum 37 will correspondingly turn.

20 As best shown in Fig. 5, the collecting drum 37 is provided at its right-hand side with an annular plate 52 having a wide opening 52a, to accommodate certain elements, whose function is to wash the interior of the drum and to precipitate the abrasive particles therein, and also to convey a portion of the salvaged abrasive to the stone cutting mechanism (not shown).

Operably supported on the frame 28 by the bracket 53 and brace bar 54 is the abrasive 30 circulating cylinder or member 36. This cylinder receives the wet abrasive residue material via the pipe 55 which is connected to a pulsator unit 56 hereinafter described, the said abrasive material being conveyed by gravity from the 35 circulating cylinder 36 via the outlet pipe 36a, and thence is conducted to the collecting drum 37. The pulsator 56 initially receives the abrasive residue material via a trough or runway 57 which conveys it from the stone cutting apparatus or 40 machine (not shown) and deposits same into a funnel-shaped hopper 58 of the pulsator unit which, as best shown in Fig. 1, may be disposed substantially as shown and beneath the tank 22.

45 A source of compressed air (not shown) impels the air via a pipe 59 to a valve 60 mounted on the bed plate 38 and adapted to be intermittently or periodically actuated by contact with either of a pair of projections 61, 62 extending from 50 a ring 63 clamped to the shaft 43. When the valve 60 is actuated by the aforesaid rotation of the shaft 43, compressed air, at comparatively high pressure, which may be, for example, one hundred pounds per square inch, will be admitted 55 to a pipe 64 also connected to the valve 60 and at its other end to a coupling member 65 secured to a pipe 66 entering the pulsator unit 56. The coupling member 65 is also connected to an automatic, pressure-operated, sequence 60 valve member, indicated generally at 67, which opens at reduced air pressure that may be, for example, ten pounds per square inch. A pipe 68 connected to the valve 67 has a Venturi outlet 68a which enters into a pipe fitting 70 connecting the outlet pipe 55 with a conical bottom member 70a of the pulsator unit 56, as hereinafter described more fully. The valve 67 functions to initially permit the rubber ball 69, that is seated on an elbow 71 secured to 70 the pipe 66 and maintained in the normal position shown by fingers 72 depending from a cover plate 73, to be thrust against and to close an opening 75 communicating with the hopper 58 of the pulsator unit. The lower and open tapered 75 end of the hopper 58 seats on a washer 73a,

located over the opening 75 and fastened on the plate 13, the latter in turn having its recessed marginal portion seated on a gasket 13b arranged on the upper edge of a cylindrical member 74 of the pulsator unit. The operation of the sequence valve 61 is such that the air blast from the Venturi outlet 68a commences almost immediately after the compressed air issuing from the outlet elbow 71 has thrust the rubber ball 69 against the opening 75, thereby closing the latter and consequently building up a pressure in the cylindrical portion 74 that in a second or two opens the sequence valve and consequently starts the venturi 68a in operation. The latter serves to clear and draw out all abrasive residue in the pipe fitting 70, which might otherwise accumulate, the air pressure in the hopper 70a meanwhile also cooperating to convey the abrasive residue therefrom.

The gear reduction unit 40 in combination with the pinions 41, 42, it is to be understood, reduces the turning of the shaft 43 to an almost imperceptible rate of rotation, or for example approximately one revolution per minute. It will be accordingly understood that the two projections or studs 61, 62, on the shaft 43, may actuate the air valve 60 at half-minute intervals to release air under comparatively high pressure into the pipe 64, and thence to the pulsator unit 56. This timing is, of course, subject to the speed of rotation deemed adequate for collecting and salvaging the abrasive material deposited in the drum 37. When desired, the effective actuation of the air valve 60 may be reduced, for example, to one actuation per minute by removal of one of the projections 61, 62.

In accordance with this invention, after the abrasive is applied to the cutting, polishing, grinding, and/or cutting machine (not shown), the residue material therefrom and consisting, as described above, of abrasive particles and stone dust will be conveyed with water as a carrier down the inclined runway or trough 57 into the mouth of the cone-shaped hopper 58 of the pulsator unit 56 whence it descends past the ball 69 seated on the open end of the elbow 71 fastened to pipe 66. The ball 69, normally maintained in the operative position shown in Fig. 3 by the fingers or studs 72, as mentioned above, is intermittently blown off the elbow and against the opening 75 to seal the latter. The abrasive residue precipitated up to this time in the conical bottom member 70 will now be removed by the combined action of the air pressure built up in the hopper and by the venturi action of the air blast from the outlet 68a. The upper conical hopper 58 is yieldingly held in the position illustrated in Fig. 3 by springs 76 connected to its upper edge and to vertically positioned studs 77 welded to the outer periphery of the cylindrical portion of the pulsator 56. A bracket or spider 78 has the outer ends of its arms apertured to receive the threaded ends 77a of the studs 77, the said threaded ends receiving wing nuts 79 which serve to retain the spider in the horizontal position depicted. The spider 78 also has a plurality of downwardly extending bars, as at 78a, whose lower ends bear on the cover 13, thereby maintaining the seal of the gasket 13b. Through the hub or central portion of the spider 78 an abutment bar 80 is protruded downwardly to a point where its head enters the hole 75 to serve as a stop for the ball 69 when the latter is driven off its seat on the elbow 71 by intermittent blasts of

air at minute or half-minute intervals as the valve 60 is operated by the slow turning shaft 43. The abutment bar 80 is anchored to the spider 78 in any suitable manner, as by the nuts 81, 82.

The intermittently operated air valve 60 functions to admit the flow of compressed air for periods of approximately two to three seconds, which we have found sufficient to effect the removal of the abrasive material from the pulsator unit 56. The valve opens as the adjacent projecting arm 61 or 62 on the ring 63 of the shaft 43 engages the valve operating lever arm 60a. When desired or necessary, the valve 60 may be manually operated by a cord 84 secured to the lever arm 60a and having a handle 85.

In Fig. 7 the component parts of the circulating cylinder are disclosed. These include a reticulated or screening cover 86 at the top of a cylindrical chamber 87 which is closed at its lower end by a dish-shaped bottom member 88 having a downwardly protruding outlet pipe 89 joined by a pipe coupling 90 to the abrasive-conducting pipe 36a, hereinbefore mentioned. The chamber 87 also houses means to circulate and diffuse the abrasive material intermittently injected therein by the compressed air blasts issuing from the pipe 55. These means comprise a socket member 91 threaded on an extension 92 of the pipe 55 and having an annular flange 93 on which a rubber ball 94 is seated. Normally closing the opening of the socket member 91 is the rubber ball 94 positioned in a cage formed by vertical fingers or studs 95 secured at their lower ends to a ring 96 fastened to the member 91. The upper threaded ends of the fingers 95 are secured by nuts 97, 98 to a pair of plates 99, 100, fastened at their margins to an annular flange 101 formed on a cylinder 102. The plate 100 is preferably formed of rubber to resist the abrasive action of the abrasive as it is blown upwardly thereagainst by air blasts from the pipe 55.

Below cylinder 102 an inclined screen element 102a is supported by an annular projection 19 from the side walls of the cylindrical chamber 87. The screen 102a is centrally apertured to receive the extension 92 of the pipe 55. A gasket 92a arranged on the said extension serves to maintain an operative sealing engagement of the adjacent parts. The screen 102a also forms a junction at its lowest point with a diagonally and downwardly extending pipe 87a. Different types of abrasive, such as shot and silicon carbide by way of example, may be blown into the circulating cylinder 87 by the pulsator 56. As these abrasives, in conjunction with water and stone dust, fall from diffusing means described above, they must either pass through the screen element or due to their size be rejected by the screen element 102a. In the case of a mixture of shot and silicon carbide, the silicon carbide, water and stone dust pass through the screen and the shot, being too large to pass the screen, roll into the pipe 87a, thus automatically separating or classifying same, from whence they may be again circulated to the cutting, grinding, polishing and/or similar purpose machines, or be separately collected; while the silicon carbide is reclaimed and recirculated, as herein described. By removing the screen, all abrasive material may be circulated and reclaimed together. A baffle 87b serves to protect opening of pipe 87a, thus keeping blown materials from entering therein.

The abrasive residue from the circulating

cylinder, as described generally hereinbefore, descends by gravity into the pipe 36a and thence falls into the drum 37, as at 103, where it lies at the bottom normally containing water 104 to the level of the edge of the opening 52a, from which the water falls into the precipitating and settling tank 22. The specific construction of the drum 37 alluded to in general above, includes a plurality of scoops or buckets 105 suitably fastened to the inner periphery of the drum and having the cross-sectional contour depicted in Fig. 6. The construction of the individual scoops is further shown in the perspective view of Fig. 9 and comprises for each scoop a pair of deflector vanes 106, 107 arranged angularly and fastened at their mutually spaced ends to a scoop or bucket element 108 which latter provides with the adjacent periphery of the drum a shelving, abrasive-receiving pocket 109.

The abrasive residue scooped up by the buckets is dumped into the mouth of a hopper (Figs. 10 and 11), designated generally at 110, which comprises a shelving screen 112 arranged between side panels 113, 114 respectively, the side panels being integrally joined at the rear by a panel 115 to which the screen 112 is also attached. Beneath the screen 112, a bottom member 112a is positioned and suitably secured to the adjacent panels. Salvaged particles of abrasive passing through the screen fall on the bottom 112a whence they are returned for reuse, as herein-after described. Larger particles of abrasive, or agglomerations thereof, are washed off the screen or broken up thence to drop back into the drum 37.

A top 115a is provided with a rectangular, cut-out portion, as at 116. Over the cut-out portion 116, a cover member 117, also having a cut-out, as at 118, is adapted to slide. The cover 117 has a bent portion 119 to which a strap 120 is secured, as at 121. The strap 120 has an angular extension 122 formed with a slot 123 slidably receiving the threaded stem of a screw bolt 124 passing through a portion of the adjacent frame 28. A wing nut 125 on the screw bolt serves to lock the strap and consequently the cover 117 in the desired position to regulate the extent of the opening 126 afforded by the coacting cut-out portions 116, 118.

The abrasive material falling through the screen bottom 112 of the hopper 110 is conveyed by a diagonally extending pipe 127 joining the said hopper and protruding through a front panel 128 thereof. This residue material, it is to be understood, will be returned via pipe 127 and pipe 129 to the stone cutting mechanism (not shown). The pipe 127 may be conveniently retained in the operative position shown by a pipe clamp or strap 130 suitably secured to an adjacent portion of the cradle frame, as at 131. In order to thoroughly remove the abrasive from the inner periphery of the drum 37 and deposit it into the pockets of the scoops or buckets 105, a pipe 132 connected to a source of water supply (not shown) and regulated by a valve 133 is inserted into the chamber of the drum, and consequently projects a stream of water therein to effect the result indicated. Another pipe 134 connected to the same source of water supply and controlled by a manually operable valve 135 also enters the chamber of the drum 37 to a point adjacent the opening in the hopper 110 between the side panels thereof in order to provide an adjustable water medium to carry the abrasive deposited in hopper 110 back to the stone operating machine (not shown).

via pipes 127 and 129. A third pipe 136 also connected to the same source of water supply through the common coupling 131 is extended horizontally into the chamber of the drum 37. This pipe is also controlled by a valve 138 and has a series of orifices 139 which function to further scour and remove all material from the inner periphery of the drum. This last-mentioned pipe 136 supports the hopper 110 by a bracket 140. Further details associated with the collecting drum 37 include the section of rubber pipe 141, which is operatively connected to the outlet pipe 36a and is conveniently supported on a bar 142 welded to an adjacent portion of the frame 28. The rubber pipe 141 may be supported in any suitable manner, as by the cord or wire 143 wrapped around the supporting rod and the outer periphery of the rubber pipe. The means for supporting the perforated pipe 136 may preferably include a bracket 143a, which is adjustably clamped to an adjacent portion of the frame 28 by screws 144 riding in slots 145 formed in the bracket 143a.

The details of the abrasive precipitating and settling tank 22 includes a series of shelves 146 which are arranged in staggered relation so that the material from the upper trays will progressively fall to the lower trays while being conveyed by the current of water. Overflow means for the tank 22 includes a casing 147 having a sight window 147a, the casing also including an outlet pipe 147b. This permits reuse of the water as a flushing medium, if desired.

In connection with the application and transmission of the power for the apparatus, and in order to prevent abrasive material or water interfering with the smooth action of the driving units and including the motor and gearing, a housing 148 encases these members, as best shown in Figs. 1 and 2.

The function and operation of the device has been in large measure described above, but may be summarized as follows:

The abrasive material flowing in the form of a wet paste from the stone cutting operation will preliminarily reach the pulsator unit 56, and thence, as described above, will be forcibly ejected into the abrasive circulating cylinder 36 at approximately half-minute intervals, as the motor 35 and the gear reduction system associated therewith communicate slow revolution to the drum 37. The abrasive residue material projected into the cylinder 36, as hereinbefore pointed out, is conveyed by the pipe 36a to the drum 37, which functions to receive all of the abrasive residue material, and in its rotation, deposit it into the hopper 110 which functions to effect a sifting and agitating action of the abrasive, that results in the precipitation of the heavier particles while the lighter material flows out of the drum in a current of water and drops into the settling tank 22 where the staggered shelves or trays 146 serve to conveniently retain it in position for scraping therefrom. The heavier particles, in large measure, are conducted by the pipe 127 to the stone cutting operation in a form suitable for immediate use.

While certain preferred embodiments of the invention are hereinbefore set forth, it is to be clearly understood that the invention is not to be limited to the exact construction illustrated and described because various modifications of the details may be provided in putting the invention into practice within the purview of the appended claims.

What is claimed is:

1. In an abrasive salvaging machine of the kind described and for use with a stone cutting machine, in combination, means connected to and receiving abrasive residue from said stone cutting machine, fluid pressure means connected to the means and effective to intermittently apply compressed air thereto, a container operably connected to the first-mentioned means and receiving the abrasive residue therefrom at intermittent intervals, a rotatable member connected to the container, a hopper in said rotatable member and receiving salvaged abrasive particles from the rotatable member, and instrumentalities for removing residue material from the interior of the rotatable member.

2. In an apparatus of the kind described and for use with a stone cutting mechanism, in combination, a frame, means on the frame to receive abrasive residue material and intermittently convey it to a container, a rotatable member turnably mounted on the frame, conduit means effective for conveying residue material from the container to the rotatable member, abrasive conveying scoop means arranged on the inner periphery of the rotatable member, a hopper supported within the rotatable member, other means for removing abrasive material from the inner periphery of the rotatable member, said hopper receiving said material as the rotatable member is turned, and other means operably associated with the member and effective for receiving abrasive residue material of comparatively light specific gravity and to precipitate abrasive particles therefrom for reuse while discarding unusable abrasive material and stone dust.

3. In an apparatus of the kind described and for use with a stone cutting mechanism, in combination, a support, an intermittently operated pulsator unit connected to said support and receiving abrasive residue for conveying purposes, a container arranged on the support and operably connected to the intermittently operated unit to receive abrasive residue therefrom, valve means within said container and operable under the influence of said intermittently operated pulsator unit is actuated, a drum turnably supported on the support, conveying means for delivering abrasive residue from said container to said drum, means including a motor and a gear reduction unit for rotating said drum at a comparatively slow rate, a plurality of instrumentalities within the drum to receive, circulate, and precipitate abrasive particles from abrasive residue material received from the container, a tank associated with the drum and arranged to receive a portion of abrasive residue material issuing from said drum, said tank having a plurality of shelves effective to precipitate abrasive particles therein, and fluid means within the tank for carrying away unusable abrasive material and stone dust.

4. In an apparatus of the kind described and for use with a stone cutting mechanism, in combination, a frame, a pulsator mechanism connected to the frame, means to convey abrasive residue material to the pulsator mechanism, fluid pressure means connected to the pulsator and intermittently operable to eject abrasive residue material therefrom, a container connected to the pulsator and receiving the said material therefrom at the intermittent intervals indicated, said container being operably connected with a rotatable drum mounted on the frame and effective to convey by gravity abrasive material thereto, a plurality of means within the drum effective

to remove abrasive material from the inner periphery thereof and to convey heavier abrasive particles from the drum to a predetermined point for reuse, a settling tank arranged adjacent the drum and receiving water-conveyed abrasive material therefrom, said last-mentioned abrasive material including lighter abrasive particles and an admixture of stone dust, and a plurality of shelves within said tank and arranged in staggered relation, said shelves being effective to precipitate a portion of the lighter abrasive particles while water operates to carry away unusable, light abrasive particles and stone dust.

5. In an abrasive salvaging machine of the kind described and for use with a stone cutting mechanism, the combination of an abrasive-receiving pulsating unit, a connection between said pulsator mechanism and the stone cutting mechanism, said connection being operable to convey abrasive residue material to said pulsator mechanism, a source of compressed air connected to the pulsator and effective to transmit air pressure at intermittent intervals thereto, conduit means connecting the pulsator to an abrasive container, a valve within said abrasive container normally effective to prevent the discharge of abrasive material back to the pulsator while permitting the entrance of the material therein, a drum operably associated with the container and receiving residue material therefrom by gravity, power operated means to rotate said drum, a hopper within the drum, said hopper receiving abrasive material from the inner periphery of the drum as it rotates, and a settling tank arranged adjacent the drum and receiving water conveyed abrasive material therefrom.

6. In an abrasive salvaging machine of the kind described and for use with a stone cutting mechanism, in combination, a frame, a source of power arranged on said frame, an abrasive-receiving pulsator mechanism connected to the frame and to the source of power, an abrasive circulating container arranged on an upper portion of the frame and connected to the pulsator, a drum connected to the source of power and operably associated with the container, a hopper within the drum and connected by conduit means to said stone cutting mechanism, gear reduction means connected to the source of power and the drum and effective to limit the revolutions of the drum to a comparatively slow speed, and other means including a source of compressed air for ejecting abrasive residue material from the pulsator mechanism, and thence to the circulating container, said circulating container depositing the residue material into the rotating drum, said drum conveying the material to the hopper, and a tank arranged beneath the drum and receiving lighter portions of the residue material and precipitating it for reuse while discarding unusable abrasive material together with stone dust.

7. A process for salvaging abrasive particles from abrasive residue material containing stone dust, which includes the intermittent forcible conduction of the abrasive residue material to a predetermined point in order to secure a preliminary dispersion of the particles thereof, then permitting the said material to descend by gravity to rotating means, then precipitating the residue material in the presence of water and to immediately secure the heavier abrasive particles thereof, and then permitting the water to convey the lighter abrasive particles to other

11

precipitating means while conveying the unusable abrasive particles and stone dust to a predetermined point.

8. The process of salvaging abrasive particles from abrasive residue material received from stone cutting operations, which comprises the initial conveyance of the abrasive residue material by water, then dispersing the material by an air blast and conveying it thereby to receiving means, then permitting the abrasive residue to gravitate to rotating means, and further agitating said material at said rotating means to obtain a preliminary precipitation of the heavier particles thereof, and finally conveying the rest of the residue material, including the lighter abrasive particles therein to a washing treatment to precipitate the lighter particles and simultaneously discard the unusable material therefrom.

9. The process of salvaging abrasive particles from abrasive residue material from stone cutting operations, which comprises the initial reception of the material, then intermittently dispersing the particles of the material by compressed fluid, then receiving the said dispersed material and permitting it to fall by gravity to rotating means, then subjecting the material while rotating to a water spray, then accumulating the heavier abrasive particles and conveying them to a predetermined point for reuse, and then conveying the lighter abrasive particles together with stone dust to other means to effect a further precipitation of abrasive particles, and finally discarding the unusable abrasive material and stone dust by conveying same to a predetermined point in the presence of water.

10. In an apparatus for the reclaiming of abrasive particles from abrasive residue containing stone dust, in combination, abrasive residue receiving means including a pulsator, a circulating container connected to said pulsator and effective to diffuse said abrasive residue, and other means connected to said container to receive residue therefrom and including a collecting member to segregate and salvage usable abrasive particles from the residue while discarding stone dust and unusable abrasive particles.

11. In an abrasive salvaging apparatus of the kind described, in combination, abrasive conveying means, an intermittently operated pulsator mechanism adapted to receive abrasive residue from the conveying means, fluid operated means within the pulsator mechanism and effective to permit the conveyance of said residue to circulating means operably connected to the pulsator mechanism, said circulating means diffusing the abrasive residue and then feeding same by gravity to a segregating and collecting mechanism, said last-mentioned mechanism including abrasive conveying and washing means, and additional means to collect usable abrasive particles from the residue while discarding the unusable residue.

12. In an abrasive salvaging machine of the kind described, in combination, supporting means, abrasive collecting mechanism carried by said supporting means, abrasive conveying means, an intermittently operated pulsator mechanism adapted to receive abrasive residue, fluid-operated means within said mechanism and effective to distribute said abrasive residue to said abrasive collecting mechanism, said abrasive conveying means being operably connected to said pulsator mechanism and effective to preliminarily collect the said abrasive residue, and then feed same by gravity to said abrasive collecting mechanism, said mechanism including means to collect com-

12

paratively heavy abrasive particles and return same to a predetermined point, and instrumentalities to precipitate lighter abrasive particles for reclamation while discarding unusable abrasive particles and residue.

13. In a device for salvaging abrasive particles from abrasive residue material, in combination, a support, means arranged on said support and intermittently operable to receive and eject abrasive material therefrom and to an abrasive container secured to the support, abrasive conducting means connected to the container and operable to convey abrasive residue material therefrom by gravity, a cylindrical member turnably supported on the support and connected to the container by the said conducting means, a hopper within said cylindrical member and coactable with abrasive receiving buckets arranged on the periphery of the drum, water supplying means operably connected to the interior of the drum and effective to remove abrasive residue material from the periphery of the drum, a pipe connected to said hopper and operable to receive precipitated and comparatively heavy abrasive particles from the hopper and to convey same to a predetermined point, and a settling tank arranged adjacent to and beneath the drum and normally operable to receive abrasive residue material therefrom, said tank having means to precipitate lighter abrasive particles while discarding the unusable lightest abrasive particles and stone dust mingled therewith.

14. In a device of the kind described, a tank mounted on a frame, means mounted on the tank and effective to rockingly support a second frame, gear reduction means connected to the motor and supported on the second frame, a drum connected to the gear reduction means and turnable thereby, an abrasive-receiving and intermittently operable unit connected to the first-mentioned frame, a source of compressed air connected to the said unit, a valve connectible to the source of compressed air and operable by the motor to intermittently cause a blast of compressed air to enter the unit, an abrasive container arranged on an upper part of the second frame and connected by a pipe to the unit, a valve within the container for preventing the return of abrasive material to the unit while permitting its admittance into the container, a second pipe connecting the container with the drum, and means within the drum including a hopper and abrasive collecting means; whereby as said motor is operated, the unit, container, and drum function to segregate heavier abrasive particles from lighter abrasive particles while discarding unusable abrasive material and stone dust.

15. A process for reclaiming and recirculating usable abrasive particles from abrasive residue, which comprises the conducting of abrasive residue by a current of water to receiving means, then dispersing the abrasive residue by air to effect a preliminary separation by screening of the heavier and usable abrasive particles from the said residue, then subjecting the remainder of the residue to a washing and flotation in water to effect a precipitation of other usable abrasive particles while permitting the unusable portion of the abrasive material to remain in suspension in the water, and then recirculating the precipitated usable abrasive particles.

16. A process for salvaging abrasive particles from the abrasive residue of stone cutting operations, which comprises the initial conveying of

said residue by a current of water to receiving means, then intermittently subjecting the residue to compressed air while in the receiving means and conveying it in dispersed form to washing means, and then precipitating usable abrasive particles from the residue and simultaneously conveying away unusable abrasive residue for discarding.

17. In an apparatus for salvaging and recirculating abrasive particles and shot from abrasive residue containing stone dust, in combination, a plurality of coactable and separable units, said units being coordinated and effective to sequentially receive abrasive residue material and then to treat the said material to progressively diffuse and segregate the usable abrasive particles from the unusable abrasive particles and recirculate the usable abrasive particles, one of said units having means to segregate shot from the rest of the abrasive residue and convey same to recirculating means.

18. In mechanism for the salvaging of abrasive particles from abrasive residue, in combination, means to receive a mixture of abrasive residue, shot and water, screening means in said receiving means, other means to disperse the particles and shot of said mixture and cooperating with said screening means to effect a preliminary segregation of heavier abrasive particles from lighter abrasive particles, and additional means to wash with water and precipitate other

abrasive particles from unusable portions of the residue while discarding said unusable residue.

19. In an apparatus for the reclaiming of abrasive particles and shot from abrasive residue containing stone dust, in combination, abrasive receiving means including a pulsator, a circulating container connected to said pulsator and effective to diffuse said abrasive residue, said container having means to segregate the shot from the rest of the abrasive residue and return same to recirculating instrumentalities, and other means connected to said container to receive residue therefrom and including a collecting member to segregate and salvage usable abrasive particles from the residue while discarding stone dust and unusable abrasive particles.
